CLAIM

The ornamental design for a zipper pull, as shown and described.

DESCRIPTION

FIG. 1 is a perspective front side view of a zipper pull of the present invention;

FIG. 2 is a front side view of the zipper pull;

FIG. 3 is a back side view of the zipper pull;

FIG. 4 is a left side view of the zipper pull;

FIG. 5 is a right side view of the zipper pull;

FIG. 6 is a top side view of the zipper pull; and,

FIG. 7 is a bottom side view of the zipper pull.

The broken lines shown in the drawings are for illustrative purposes only and form no part of the claimed design.
